Company, Rochester, N. Y., a corporation of
New Jersey

Application December 29, 1941, Serial No. 424,794

4 Claims. (Cl. 95—1.1)

This invention relates to color photography and particularly to methods and means for labeling color prints.

In certain processes of making color prints from color negatives or transparent positives the processing includes flash exposures of the blue and green-sensitive layers from the front and a flash exposure of the bottom and red-sensitive layer through the support. It has been found that any number printed on the back of the prints masks the red-sensitive layer during this flash exposure and causes the numbers to be reproduced in the cyan layer, i. e. the red-sensitive layer.

It is the object of the present invention to provide a method and means for marking the backs of prints so that the number will not show in the picture itself.

Of course, whatever ink is used for labeling the prints should be such that it may be easily applied to the back of the paper at the time the first exposure is made or immediately thereafter. Therefore, the ink should be a quick-drying ink and after it has dried, it should be compatible with the processing solutions and with the photo-sensitive layer in case the back of one print comes in contact with the front of another. Also, the ink should not be removed or removable by the processing solutions. These properties of the ink are all necessary ones if the color process is not to be spoiled in any way.

According to the invention an ink is selected which is completely transparent to red light, at least prior to the immersion in the solutions employed in the process after the red flash exposure. The backs of the prints are labeled with this ink effectively at the time the first exposure is made and the ink is visible after the process is completed.

There are three possible species of this invention. Of these the most preferable one is a dye completely transparent to red light, yet having a fairly high white light density, specifically a magenta dye dissolved in Cellusolve. This solvent is "ethoxyethanol" or ethylene glycol monoethyl ether. It is selected because it is quick drying, and when dry is not removed by the processing solutions, does not affect the processing solutions, is compatible with the photosensitive emulsions, and does not affect the rubber or artificial rubber used in the making of numbering stamps with which the ink is applied. It is, of course, a solvent for the magenta dye used, which may be any of the magenta dyes employed in color photographic processes.

A second species of the invention employs an ink consisting of a slow, red-sensitive emulsion which is not exposed by the first exposure of the print, but is exposed by the red flashing exposure and, hence, develops up in subsequent processing solutions to give a visible image. This is not as satisfactory as the magenta dye in the Cellusolve, because the intensity of the label depends upon the intensity of the red flash exposure and because it is not as easy to apply.

A third species consists of using an invisible ink, which is rendered visible by immersion in an additional solution after the completion of the color process itself. For example, the invisible ink may be a starch and the prints may be immersed in a dilute solution of iodine to bring out the characteristic color. The disadvantage of this species is, of course, the need for an additional processing solution.

The invention will be fully understood when the following description is read in connection with the accompanying drawing in which:

Fig. 1 shows a color printing process in which the invention has been applied.

Fig. 2 shows the back of a color print carrying a serial number applied according to the present invention.

In Fig. 1, light from a source 10 illuminates a color transparency 11 and projects an image of it by means of a lens 12 onto a color-sensitive layer 13 unwound from a supply roll 14. At the time this exposure is made, or immediately before or immediately thereafter, an identifying mark such as a serial number is placed on the back of the print. In the example shown, the layer 13 is advanced to the next exposure position before the serial number is applied by a rubber stamp 52 while the front of the print is held against a support 53. According to the invention this print is marked with an ink which is completely transparent to red light. After exposure, the color film 13 is moved as indicated by the broken line 15 to the processing solutions. The broken line 15 may include winding up of the film 13 and unwinding into the processing solutions as indicated by the portion 16 of the film. The various parts of the process are only indicated schematically, but they include flashing of the photosensitive layer from the front by means of light from a source 19 through a filter 20, striking the film 13. The film is then immersed in further processing solutions as indicated at 26, and the broken lines 17 and 25 may include other immersions in solutions or other similar exposures. After further processing, as indicated by the broken line 27, the

film as shown at 28 is exposed to a flash exposure from a light source 30 through a red filter 29 and through the support for the sensitive layer on the film 28. According to the invention, the ink for labeling the number on the back of the print is such that this flash exposure is not affected in any way by the presence of the ink. Subsequent steps in the process are indicated at 31, 32, and 33. Afterwards the film 35 is cut by a suitable tool 36 and 37 so that a pile 38 of prints are provided on a table 39. According to the invention, the ink applied by stamp 52 is such that it is plainly visible on the back of each print in the pile 38.

If, after the number is applied by the stamp 52, the film is wound up before processing, the ink comes in contact with the surface of the sensitive emulsion. Similarly in the final, completely processed prints 38 the number is in contact with the surface of the color print. Therefore, the ink should be such that it is compatible with the color layers both before and after processing.

In Fig. 2 the back 50 of a color print is shown having the number 51 printed thereon at one end of the print.

Various forms of printing stamps are satisfactory, but we prefer to use one of the type having an automatic closing inking chamber so that the quick-drying ink will not be exposed until used.

Having thus described our invention, we wish to point out that it is not limited to this method and

particular apparatus, but has the scope of the appended claims.

What we claim and desire to secure by Letters Patent of the United States is:

- 5 1. In a process of printing from a multicolored record, which process includes exposing a color-sensitive layer on a support and immersing the layer in solutions, flashing the layer with red light through the support and immersing it in subsequent solutions, the method of labeling prints which comprises marking on the back of each exposed area at effectively the same time as said exposing with a quick-drying ink which, when dry, is not removed by any of the said solutions, 10 is compatible with said sensitive layer, and at least prior to said immersing in subsequent solutions is completely transparent to red light.
- 15 2. A method according to claim 1, in which the marking is done with a magenta dye in Cellulose.
- 20 3. A method according to claim 1 in which the marking is done with a slow, red-photosensitive, transparent ink which, when exposed to red light, is rendered developable in said subsequent solutions to form a visible material.
- 25 4. A method according to claim 1 in which the marking is done with a starch solution and the back of the prints are brought into contact with a dilute solution of iodine after said immersion in 30 subsequent solutions.
